UNITED STATES PATENT OFFICE.

DAVID PUDLIN, OF NEW YORK, N. Y., ASSIGNOR TO PIONEER NOVELTY MANUFACTURING CO., OF NEW YORK, N. Y., A CORPORATION OF NEW YORK.

EYE FOR DOLLS.

1,187,926.

Specification of Letters Patent. Patented June 20, 1916.

Application filed February 9, 1915, Serial No. 7,019. Renewed March 31, 1916. Serial No. 88,173.

To all whom it may concern:

Be it known that I, DAVID PUDLIN, a citizen of the United States, and a resident of the city of New York, borough of the Bronx, 5 in the county of the Bronx and State of New York, have invented a new and Improved Eye for Dolls, of which the following is a full, clear, and exact description.

This invention relates to eyes especially 10 adapted for dolls, although they are not necessarily limited to this use.

The general objects of the present invention are to provide an unbreakable eye of novel, simple and inexpensive construction 15 and having a close resemblance to a natural eye.

A more specific object of the invention is the provision of an eye comprising a shell of celluloid or equivalent material which bears 20 the iris and pupil and is filled with plaster of Paris or equivalent material, whereby the shell will maintain its spherical form and be rendered unbreakable, the shell being made of two approximately hemispherical pieces 25 of celluloid fitting one within the other, the inner one being white and the other transparent, and on the inner piece the iris and pupil are applied, as by photolithographing, or any other suitable method.

With such objects in view, and others 30 which will appear as the description proceeds, the invention comprises various novel features of construction and arrangement of parts which will be set forth with particularity in the following description and claims appended hereto.

In the accompanying drawing, which 35 illustrates one embodiment of the invention, and wherein similar characters of reference 40 indicate corresponding parts in all the views, Figure 1 is a side view of the eye; Fig. 2 is a front view; Fig. 3 is a vertical section; and Fig. 4 shows the two pieces of the shell before the same are nested together.

Referring to the drawing, 1 designates 45 the body of the eye, which body is spherical, and contained in the shell 2, which carries the pupil 3 and iris 4, and embedded in the body is an attaching device 5 of any approved character.

The shell 2 is approximately hemispherical and is hollow so that when filled with plaster of Paris that forms the body 1, the

shell will be internally supported so that there is no danger of breakage or indenting. 55

To retain the shell in place the edge of the open side thereof is provided with scallops 6 which are bent inwardly, and embedded in the soft plaster of Paris. By thus scalloping the edge and contracting the open side 60 of the shell the said open side will be of smaller diameter than the maximum diameter of the filling or body 1, whereby it is impossible for the shell to become detached.

In making the shell the same is constructed 65 of two parts 7 and 8, as shown in Fig. 4, and the material is preferably celluloid or the like. The inner part 8 is white celluloid so as to form the white part of the eyeball, and the outer part 7 is transparent. The 70 pupil 3 and iris 4 are photolithographed or otherwise applied to the external surface of the part 8, and are visible through the transparent outer part 7. These two parts 7 and 8 are chemically united under pressure by 75 any well known process, so that the shell becomes an integral structure.

An eyeball constructed as set forth is of 80 comparatively simple and inexpensive construction and is unbreakable under ordinary circumstances.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have 90 it understood that the device shown is merely illustrative and that such changes may be made when desired as are within the scope of the appended claims.

Having thus described my invention, I 95 claim as new and desire to secure by Letters Patent:

1. An eye for dolls and the like, comprising a shell of celluloid and bearing the pupil and iris, and a hard filling formed of plastic material in the shell.
2. An eye for dolls and the like, comprising a shell made of a white inner part and a transparent outer part, the inner part bearing the pupil and iris, and a hard substance 105 completely filling the shell.

3. An eye for dolls and the like, comprising a shell bearing the pupil and iris, said shell being made of tough, yielding material and of approximately hemispherical form;
- 5 the edge of the open side of the shell being formed into scallops, and a body formed of plastic material filling the shell and into which the scalloped edge is anchored.
4. An eye for dolls and the like, comprising an approximately hemispherical shell of celluloid having an open side, the edge of

the open side of the shell being scalloped and contracted, and a body of hard material filling the shell.

In testimony whereof I have signed my 15 name to this specification in the presence of two subscribing witnesses.

DAVID PUDLIN.
